**PORTABLE, OIL-BURNING, COMBINED RADIANT
AND HOT-AIR-BLOWING HEATER**

Rallston M. Sherman, Glastonbury, Conn., assignor to
The Silent Glow Oil Burner Corporation, Hartford,
Conn., a corporation of Connecticut

Application June 29, 1954, Serial No. 31,227

Term of patent 14 years

(Cl. D81—10)

FIG. 1

FIG. 3

FIG. 2

Fig. 1 is a side elevational view of a portable, oil-burning, combined radiant and hot-air-blowing heater, showing my new design;

Fig. 2 is an end elevational view of the heater as viewed from the left of Fig. 1; and

Fig. 3 is an end elevational view of the heater as viewed from the right of Fig. 1.

The top of the heater illustrated in Figs. 1, 2 and 3, except for its rounded edges, presents a flat plain surface. The side of the body portion of the heater opposite the side thereof illustrated by Fig. 1 is identical with the side so illustrated.

I claim:

The ornamental design for a portable, oil-burning, combined radiant and hot-air-blowing heater, substantially as shown and described.
